PRINTING ENLARGING MACHINE

Alvin L. Mayer, Cincinnati, Ohio

Application July 23, 1935, Serial No. 32,687

9 Claims. (Cl. 88—24)

This invention relates to photographic apparatus, and more particularly to a machine for enlarging and printing photographic negatives.

One of the objects of the invention is to provide a printing enlarging machine in which the negative to be printed may be viewed in its enlarged size prior to the printing exposure.

Another object is to provide a printing enlarging machine in which the photographic print may be readily inserted in exposure position, firmly held in such position during exposure and automatically released therefrom after exposure.

Still another object is to enable the photographic print to be numbered while in exposure position.

A still further object is to provide a simple and convenient means for supporting the photographic negative in position for projection of its image upon the printing medium.

Another object is to enable the negative strip to be advanced through the exposure gate of the machine and to be severed into its individual exposures.

Another object is to provide means for clamping back the negative film and positive paper in exposure position, numbering the positive paper or print, making the exposure, severing the previously exposed negative from the strip and releasing the positive print, all by a single operation of the operator.

Other objects and advantages of the invention will hereinafter appear.

The invention will be best understood by reference to the following drawings in which:

Fig. 1 is a vertical sectional view of a printing enlarging machine embodying my invention;

Fig. 2 is a plan view thereof;

Fig. 3 is a sectional view on the line 3—3 of Fig. 2, showing the print retaining element in normal position;

Fig. 3A is a similar sectional view showing the print retaining element in open position;

Fig. 4 is a sectional view on the line 4—4 of Fig. 2;

Fig. 5 is a right end elevation as seen in Fig. 2;

Fig. 6 is a sectional view on the line 6—6 of Fig. 2;

Fig. 7 is an enlarged sectional view on the line 7—7 of Fig. 1;

Fig. 8 is an enlarged fragmentary sectional view of the central portion of Fig. 6, and may be considered as viewed substantially on the line 8—8 of Fig. 7;

Fig. 9 is a sectional view on the line 9—9 of Fig. 1;

Fig. 10 is a sectional view on the line 10—10 of Fig. 6;

Fig. 11 is a sectional view on the line 11—11 of Fig. 10;

Fig. 12 is a sectional view on the line 12—12 of Fig. 1, showing the filter and shutter mechanism;

Fig. 13 is a sectional view on the line 13—13 of Fig. 1;

Fig. 14 is a sectional view on the line 14—14 of Fig. 1;

Fig. 15 is a side elevation of the film supporting mechanism for single exposure films;

Fig. 16 is a plan view of the modification of Fig. 16; and

Fig. 17 is a sectional view thereof on the line 17—17 of Fig. 15.

Referring first to Figs. 1, 2 and 5, I have provided a printing enlarging machine comprising a base composed of two leg castings 20 and 21 and a bed casting 22. The leg standards 20 and 21 are held spaced apart by the tie rods 23 and 24 passing through bosses 25 in the leg standards and having clamping nuts disposed on opposite sides of said bosses.

Mounted upon the bed casting 22 is a condensing lens housing 26 secured to the bed casting by suitable screws or bolts 27. The inner wall of the lens housing is recessed to provide a shoulder 28 against which one element 29 of the condensing lens system is held by the clamps 31 and 32. A second lens element 33 is secured in the recess, in contact with the clamps 31 and 32 by a ring 34 secured to a shoulder 35 formed by a further recess or counterbore in the lens housing.

The lens housing is disposed adjacent a lamp housing 36. The lamp housing comprises a rectangular chamber 37 with a tubular lamp 38 axially mounted therein on a base 39, supported in the base of the housing in such manner as to provide air passages 41 through the base of the housing. The conical dome 42 is provided with a light proof ventilating cover 43 whereby to permit a natural draft circulation through the housing. Apertures 44 are provided in each of the four sides of the housing, these apertures having spaced sleeves 45 and 46 extending outwardly therefrom between which the cylindrical lens house extension 47 telescopes.

It is contemplated that four printer enlarging machines will be provided for each lamp housing, the lens housings 26, 48, 49 and 50 of which are partially shown in Fig. 2. One complete machine, associated with lens housing 28, only is shown.

The forward end of each lens housing ter-

minates in a rectangular opening or film gate 51 and mating with this opening is a pressure plate 52 having a corresponding opening. The upper adjoining edges of the film gate and pressure plate are beveled as shown at 53 to facilitate entrance of the film strip. The pressure plate 52 is mounted upon two pins 54 and 55 carried by arms 56 and 57, respectively, pivoted upon a pin 58 (Fig. 10) mounted in lugs 59 on the lens housing.

The arm 57 is of substantially a reversed C-shape and has adjacent the upper end thereof, a small pin 61 fitting loosely in an opening in the side of the pressure plate, the purpose of which will appear hereinafter.

The pressure plate is normally spaced slightly away from the film gate to permit the film to be inserted therebetween. A spring pressed detent 62 provided in the upper wall of the film gate holds the film in adjusted position relative to the film gate and its associated pressure plate. However, prior to exposure the arms 56 and 57 are rocked about their pivot pin 58, in a manner to be described hereinafter, to force the pressure plate against the film gate whereby to clamp the film F therebetween and to stretch the film so as to hold the same in a plane, free from warping, during the actual exposure period. During the movement of the pressure plate, the loose fit of the pin 51 permits the pressure plate to adjust itself parallel to the face of the film gate.

A tapered housing 63, carried by a standard 64, secured to the bed casting 22 is telescopically associated with an extension of the pressure plate 52 and mounted in the forward end of the housing 63 is a projection lens 65. The lens 65 is continuously open during operating periods of the printer.

Mounted immediately in front of the lens 65 is a filter 66 of such nature as to block all light coming through the lens of a nature capable of having a fogging effect on the photographic printing paper employed. The filter 66 is mounted on a shutter element 67 (Fig. 12) formed on a bell crank 68 pivotally mounted on a shaft 69 carried by a bracket 71, secured to the bed casting 22. A second, cooperating shutter element 72 is carried by a bellcrank 73 similarly pivoted on shaft 69. Links 74 and 75 connect the free arms of the bell cranks to an arm fixed to a rock shaft 77. As a result of these connections, the action of rock shaft 77, rotating in the direction of the arrow (Fig. 12), pulls down on links 74 and 79, moving the shutter elements 67 and 72 in the direction of the arrows. This movement causes the shutter elements 72 and 67 to move across each other, removing the filter 66 from in front of the lens and at the same time obstructing the passage of light from the lens by the overlapped portions of the shutter. As the shutter elements continue to move past each other the arcuate portions 78 and 79 thereof overlap to provide an opening in front of the lens 65. When this occurs light passing through the film F is projected onto the printing paper, as will more fully appear subsequently.

Mounted on the top of the lens housing 26 is an angle bar 81 over which the film F is draped, the film passing from the supporting bar 81 downwardly between the gate 51 and the pressure plate 52, emerging at the lower end thereof, at which point shearing means is provided for severing the strip of film into its individual exposures. The shearing means comprises a stationary blade 82 secured to the lower front

edge of the lens housing and a movable blade 83 (Figs. 1, 7 and 8) pivoted on a vertical pin 84 passing through a bracket 85 secured to the front of the lens housing. A spring 86 disposed about the pin 84 urges the blade 83 upward into engagement with the blade 82. An adjustable abutment screw 87 maintains the blade 83 parallel to the blade 82 whereby uniform shearing action is obtained throughout the length of the blades 82 and 83.

The blade 83 is normally held away from the blade 82 by engagement of the curved end 88 (Fig. 2) of a lever 89, engaging a pin 91 extending downwardly from the blade 83. The arm 89 is fixed to the upper end of a rock shaft 92 journaled in a bearing 93 in the bed plate 22. A crank arm 94 fixed to the lower end of the rock shaft 93 terminates in a ball 95 engaging between the forked end 96 of a rocker arm 97 fixed to a rock shaft 77. Consequently upon movement of the shaft 77 in one direction, in a manner to be subsequently described, the arm 89 is moved towards the blade 83. A pin 98 extending up from the arm 89 engages the blade 83 and moves it towards the blade 82 to sever the depending strip of film. A spring 99 secured to the pin 98 and to a cross-arm 101 extending between the pressure plate operating arms 56 and 57 forces the pressure plate 52 towards the film gate 51 when the arm 89 is operated towards the blade 83.

Mounted beneath the bed plate 22 is a pair of envelope supporting members 102 and 103, the former of which is stationary and the latter of which is pivoted at 104 to lugs bent up from the fixed member 102. A counterweight 106 carried by the movable member 103 urges the members 102 and 103 apart to thus retain an envelope 107 on the lower end of the members 102 and 103. Member 102 extends beneath the blades 82 and 83 and forms a chute for guiding the severed pieces of film into the envelope 107.

The positive paper upon which the enlargement is to be made is supported at the right hand end of the machine between a rigid frame member 110 forming the vertical portion of a right angled bracket 111 secured to the bed plate, by suitable screws. The frame member 110 has a rectangular opening or paper frame 109 therein of the size and shape of the portion of the printing paper to be exposed. A pressure plate 112 is carried by a casting 113 (Fig. 13) mounted on trunnions 114 carried by two lever arms 115 and 116 (Fig. 5) pivoted at their lower ends on pins 117 and 118 respectively, carried by lugs extending from the bracket 111. A stirrup 119 connects the lever arms 115 and 116. An actuating link 121 is pivoted to the stirrup 119 centrally thereof and to a pin 122 extending through a lever arm 123. A spring 124 seated in a recess in the lever arm 123 surrounds the pin 122 and applies a resilient pressure to the stirrup 119 and hence to the pressure plate 112. The pressure plate is normally held away from the frame member 110 by the lever 123, so as to permit a sheet of photographic paper to be inserted downwardly therebetween. The lever arm 123 is fixed on a pin 125 pivoted in bosses formed in extensions 126 of the bed plate 22. The arm 123 is curved under the bed plate and is connected by a spring 127 to the upper end of a link 128 pivotally secured at its lower end to a foot treadle 129, pivoted on the cross brace 24. Downward movement of the treadle 129 draws the lower end lever 123 downward, forcing the pressure plate 112

112 against the frame 110 to hold the paper therebetween. The lever 123 is provided with adjustable stops 131 and 132 comprising nuts threaded on a rod 133 depending from the bed plate 22. A lug 134 extending from the rear of the casting 113 (Fig. 13) has a guide pin 135 engaged in an inclined slot 136 in bracket 137 secured by screws 138 to the vertical portion 110 of the bracket 111.

10 A link 139 is pivoted at the upper end of the pressure plate operating arm 116 and has its opposite end pivotally secured to a slide 141 operating between guides 142 and 143 formed in the bracket 137. A link 144 is pivoted to a lug 145 extending to the side of the slide 141 and serves to operate a bell crank lever 146 pivoted at 147 at the upper side of the vertical supporting plate 110. Secured to the long arm 148 of the bell crank lever is a U-shaped screen 149 adapted in the raised position of the treadle to be positioned in the rectangular opening 109 in the plate 110, adjacent the pressure plate 112 and substantially in the plane of the photographic paper, as shown in Figs. 1 and 4 and to be pivoted away from the opening 109 to expose the photographic paper as shown in Figs. 2 and 14 when the foot treadle is depressed.

The upper end of the pressure plate operating arm 115 has a link 151 pivoted thereto, the opposite end of the link being slotted at 152 for the reception of a guide pin 153 (Fig. 3). Pivoted at 154 to an extension of the plate 110 is a depending arm 155 carrying a pair of horizontally disposed paper retaining fingers 156 normally extending through slots 157 in plate 110 (Fig. 5) and across the opening between the plate 110 and the pressure plate 112. The purpose of the fingers 156 is to support the paper as it is inserted between the gate 109 and the pressure plate 112. A trip dog 158 on the pivot 154 is retained against a stop pin 159 (Fig. 3A) on the arm 155, by a spring 161. A lug 162 extending downwardly from the link 151 is adapted to engage a lug 163 on the upper side of the trip dog 158 in such manner that on the movement to the left of the link 151, the lugs 162 and 163 cam past each other with slight tilting of the dog 158 and on the reverse movement to the right of the slide 151 the lugs engage each other to pivot the arm 155, as shown in Fig. 3A, so as to withdraw the fingers 156 from beneath the paper supported thereon whereby to permit the paper to drop from between the gate 109 and the pressure plate 112. At the end of the pivotal movement of the arm 155, the lug 162 slides by lug 163 releasing the arm 155 to return to normal under the action of a spring 164. A dash pot 165 connected by link 166 to the arm 155 delays this return movement sufficiently long to insure that the fingers 156 will not catch the paper as it drops clear of the pressure plate.

A number stamp 167 of conventional design is mounted behind the pressure plate at the upper end thereof on brackets 168 secured to the rearward extensions 169 of the plate 110 (Fig. 2). It is adapted to be operated by the spaced arms 171, pivoted at 172 to the upper end of the lever 123 and actuated by a cross bar 173 (Figs. 1 and 14) through a spring 174 surrounding a cap screw 175 secured in the upper ends of the lever 123. The spring connection permits the lever 123 to rock slightly after the number stamp has been brought into engagement with the rear side of the paper. The pressure plate 112 is cut away 75 at its upper end, as shown at 177 (Figs. 1 and 14)

to permit the face of the stamp to impinge upon the paper supported ahead of the pressure plate. The stamp may also be operated by the knob 178 independently of the lever 123.

The operation of the apparatus is as follows: 5 When enlarged prints are to be made, the shutter, if any, associated with the lens 65 is continuously open and the lamp 38 continuously lighted. The envelope 107 is inserted in the slot 179 ahead of the number stamp and a number is printed thereon by pressing the knob 178 of the stamp. The numbered envelope is then placed on the supports 102 and 103 beneath the bed plate. A strip of film is next inserted in the film gate ahead of the pressure plate 52 and retained in position by the detent 62. The outer face of the screen 149 being provided with a suitable reflecting surface, the image from the film is projected thereon by the lens 65, through the filter 66. The film is adjusted in its aperture 10 while the image is being viewed on the screen 149 until the enlarged image is properly positioned on the screen, and the exposure time and type of paper to be used are estimated by the nature and brightness of the image on the screen. 15 The attendant thereupon inserts a sheet of unexposed photographic paper of the desired type in the paper gate ahead of the pressure plate 112 and thereafter depresses the foot treadle. As the treadle starts to descend it rocks the shaft 77 thereby operating the pressure plate 52 through the levers 97, 94 and 89, spring 99, and arms 56 and 57 to thus firmly press the film against the margins of the film gate. The lever 89 also actuates the blade 83 to sever the portion of the film 20 from which the previous enlargement was made. The severed portion of the film drops down into the envelope 107. During this same time, the pressure plate 112 is forced against the sheet of photographic paper by the spring 127, lever 123 25 and arms 115 and 116, to press the paper against the margins of the paper gate 109. The number stamp is at the same time brought into engagement with the back of the paper by lever 123, spring 174 and pivoted arms 171, to impress thereon the same number previously printed on the envelope. During this time the shutter members 61 and 72 are moved toward each other by lever 76 and links 74 and 75 to block off the lens 30 40 and at the end of the downward movement of the treadle, to bring the arcuate portions 78 and 79 of the shutter, before the lens, to permit the image from the film to be projected into the opening or paper gate 109. Just previous to this the screen 149 is swung out to the position shown 45 in Fig. 2 to expose the paper to the projected light. The projection of the image on to the paper occurs, as stated, at the end of the movement of the treadle and after the completion of 50 the stamping and severing operations so that the vibration or jar incident to such operations will not affect the exposure. The treadle is held depressed for the period of exposure as judged by the previewed image on the screen 149, after 55 which it is released. On the forward movement of the arm 115 to operate the pressure plate, the lug 162 on the slide 151 passed ahead of the lug 163 on the dog 158, as previously described and on release of the foot treadle, as the lever 123 60 is returned to normal by the spring 127, the slide 151 trips the arm 155 to remove the fingers 156 from beneath the paper. The pressure plate 112 at the same time releases the paper permitting it 65 to drop into any suitable receptacle (not shown) 70 75

disposed therebelow or it may drop on to a conveyor which carries it to the developing position.

It will be noted that both the envelope and the print are correspondingly numbered; that the 5 film is severed automatically by the same operation effecting the exposure and the severed portions are dropped into their envelope without manual handling. After development of the 10 prints, they are sorted and inserted in the envelopes correspondingly numbered. The enlarged image is viewed in the plane of the paper before exposure thus permitting adjustment of the position thereof and the time of exposure to be conveniently judged. The number of operations required to make the enlargements is 15 reduced to a minimum consistent with properly timed and positioned exposures.

In Figs. 15 to 18 I have shown a modification of the film gate adapted for enlargements from 20 films containing a single exposure. In this modification the pressure plate 52 is operated independently of the treadle by a spring 180 secured to the arm 51. A handle 181 enables the pressure plate 52 to be released for insertion and removal 25 of the film. The cutting blades, of course, are eliminated in this modification.

While I have shown specific embodiments of my invention, it is to be understood that the invention is not limited to the exact details of construction shown and described, but is susceptible 30 to various changes and modifications without departing from the spirit or essential attributes thereof.

What I claim is:

- 35 1. In a photographic device, a film support, a paper support, a projection lens associated with said film support to project the image from a film supported thereby onto a photographic paper supported by said paper support, a shutter for said lens, a projection screen normally disposed between said paper support and said lens, means for moving said screen from between said lens and paper support, means for moving paper supported by said paper support into the plane previously occupied by said screen and means interconnected with said screen and paper moving means for operating said shutter to expose said paper after the movement of said screen from between the lens and paper support.
- 40 2. In a photographic device, a film support, a paper support, a projection lens between said film support and said paper support, a projection screen normally disposed between said lens and said paper support and adjacent the plane of the paper supported thereby, a shutter for said lens, means for moving said screen out of the field of projection of said lens, means for moving the paper supported by said paper support into the plane previously occupied by said screen and means interconnected with said screen and paper moving means for operating said shutter to expose said paper after the movement of said screen from between the lens and the paper support.
- 45 3. In a photographic device, a film support, a paper support, a projection lens between said film support and said paper support, a source of light disposed to the side of said film support opposite to said lens, a projection screen normally disposed between said lens and said paper support and substantially in the plane of the paper supported thereby, a light filter of such nature as to block out substantially all light coming through the lens of a nature capable of having a fogging effect on the photographic printing paper em-

ployed, said filter being disposed between said lens and said screen and means for concurrently moving said filter and said screen out of the projection field of said lens.

4. In a photographic device, a film support, a 5 paper support, a lens positioned between said film support and said paper support, a source of light for illuminating said film, a projection screen normally positioned between said lens and said paper support, a light filter normally positioned between said lens and said screen, a shutter for said lens, and means for sequentially removing said filter from the projection field of the lens, closing said shutter, removing said screen from the projection field of the lens, and opening 10 said shutter.

5. In a photographic device, a film frame, means forming a guideway to facilitate the manual insertion and adjustment of film in said film frame, a pressure plate, a photographic paper 20 frame, a pressure plate for said paper frame, a lens positioned between said film frame and said paper frame, a shutter for said lens, means for bringing said first mentioned pressure plate into engagement with said film frame, means for simultaneously bringing said second mentioned pressure plate into engagement with said paper frame, means for opening said shutter, means for delaying the operation of said last mentioned means until after the operation of said 25 first and second mentioned means, all of said means being interconnected, and an element operable by a single manipulation of an operator for effecting the operation of all of said means in the order named. 35

6. In a photographic device, a film frame, a pressure plate therefor, a film severing device, a photographic paper support, a lens positioned between said film frame and said paper support, a shutter for said lens and means controlled by a 40 single operation of an operator for bringing said pressure plate into engagement with said film frame, operating said film severing device and thereafter opening said shutter.

7. In a photographic device, a film support, a 45 paper support, a film severing device associated with the film support, a numbering stamp associated with the paper support, a lens positioned between the film support and the paper support to project an image from the former onto the latter, means for operating said film severing device, means for operating said numbering stamp, means for exposing paper supported in said paper support to light projected from film supported in said film support and an element operable 50 by a single manipulation of an operator for effecting operation of all of said means. 55

8. In a photographic device, a film frame, a pressure plate therefor, a paper frame, a pressure plate for the paper frame, a severing device associated with said film frame for severing portions of a film strip as the strip is advanced past the frame, a numbering device associated with the paper frame for printing a number on a sheet 60 of photographic paper supported therein, a lens positioned between said film frame and said paper frame, a shutter therefor, means for bringing said first mentioned pressure plate into engagement with said film frame, means for simultaneously 65 bringing said second mentioned pressure plate into engagement with said paper frame, means for operating said film severing device, means for operating said numbering stamp, means for operating said shutter and an element operable 70 75

by a single manipulation of an operator for effecting operation of all of said means.

9. In a photographic device, a film support through which a strip of film may be advanced, a severing device for cutting said strip of film into sections as it is advanced through the support, means for supporting an open envelope beneath

said support, a paper support, means for projecting images of the film, as it passes through said film support onto said paper support, and means for guiding the severed sections of film into said open envelope.

ALVIN L. MAYER.
